TANTALUS SET

Andrew Cravaritis, New York, N. Y., assignor to
 National Silver Deposit Ware Co., Inc., New
 York, N. Y., a corporation of New York

Application July 24, 1937, Serial No. 155,427

5 Claims. (Cl. 65—5)

My present invention relates generally to Tantalus sets.

By the term "Tantalus set", as used herein and in the appended claims, I intend to refer to an assembly of parts consisting of one or more stoppered bottles, and a holder comprising a base plate adapted to support the bottle or bottles thereon, and a top plate adapted to snugly overlie the bottle or bottles. Usually, a set of this character comprises two bottles of substantially rectangular cross-section, arranged side by side, and each bottle is usually provided with a removable stopper of square cross-section. For illustrative purposes, I have, therefore, chosen to illustrate and describe my invention in connection with a set of two bottles of this type.

It is a general object of my invention to provide a new and unique means for locking the bottles against unauthorized withdrawal.

Briefly, my invention is characterized by the provision of a flange on either the base plate or the top plate, the flange comprising a fixed portion and a complementary adjustable portion, these flange portions normally serving, collectively, to encircle the adjacent end of the bottle or bottles to prevent withdrawal of the latter. I provide means whereby the adjustable portion may be swung aside to permit lateral withdrawal of the bottle or bottles; and I also provide a means for locking the adjustable flange portion in its normal position.

In the preferred embodiment, the flange is associated with the base plate.

A feature of my invention lies in arranging the adjustable flange portion in hinged relation to the plate, so that the flange portion may be swung outwardly into the plane of the plate when it is desired to effect a lateral withdrawal of the bottle.

I achieve the foregoing objects, and such other objects as may hereinafter appear or be pointed out, in the manner illustratively exemplified in the accompanying drawing, wherein—

Figure 1 is a perspective view of a Tantalus set embodying the features of my present invention;

Figure 2 is an enlarged cross-sectional view taken substantially along the line 2—2 of Figure 1, with parts broken away for the sake of compactness of illustration;

Figure 3 is a cross-sectional view taken substantially along the line 3—3 of Figure 2; and

Figure 4 is a perspective view of a modification.

I have illustratively shown two rectangular bottles 10 and 11, the necks accommodating the removable stoppers 12 and 13, respectively. These bottles are adapted to stand side by side upon a base plate 14 which is preferably provided with feet 15. Snugly overlying the stoppered bottles is the top plate 16 which forms

the upper portion of a continuous strap whose side portions 17 extend downwardly and are permanently secured at their lower ends to the base plate 14.

In accordance with my invention, I have shown in Figures 1—3 a flange mounted upon the base plate 14 and consisting of the fixed portions 18, 19, and 20, and the complementary adjustable portion 21. The lower ends of the strap 17 are preferably secured to the fixed flange portions 18 and 20, as indicated most clearly in Figures 1 and 3.

The adjustable flange portion 21 is hinged, as at 22, to the base plate 14 so that it may be swung from the normal full-line position of Figure 2 to the open dot-and-dash position of this figure. When the portion 21 is in its normal position it serves, conjointly with the fixed portions 18, 19, and 20, to snugly encircle the bottles 10 and 11. This prevents unauthorized removal of the bottles. When the portion 21 is swung aside, as indicated in Figure 2, either or both of the bottles may be withdrawn laterally from the device and may be replaced in the same manner.

In accordance with my invention, I provide a means for locking the adjustable flange portion 21 in its normal position. I accomplish this by mounting a tongue 23 on the base plate 14, this tongue comprising a relatively narrow strip of material, preferably metal, arranged in a plane perpendicular to the base plate 14 and projecting outwardly beyond one edge of the plate 14. In the illustrated embodiment, the tongue has a perforation 24 adapted to receive a small padlock 25. The flange portion 21 is provided with a slot 26 adapted to permit passage of the tongue through it.

When the padlock 25 is in position, the flange portion 21 cannot be swung aside; but when the padlock 25 is removed, the flange portion 21 may be freely swung into the dot-and-dash position of Figure 2.

Where the Tantalus set comprises two bottles, side by side, as indicated in the drawing, the tongue 23 is preferably arranged between the bottles.

The invention is equally applicable to the top plate 16, as indicated in Figure 4. In this figure, I have applied the same reference numerals 10, 11, 12, and 13 to the stoppered bottles. The base plate 27 is in this case provided with no flange at all, or with the very shallow ornamental flange shown in Figure 4. Secured to the base plate are the upwardly extending straps 28 merging at the top with the top plate 29 which snugly overlies the bottles. In this embodiment, a flange is secured to the top plate 29, and consists of the fixed portion 30 and the adjustable flange portion 31. The latter is preferably hinged, as at 32, and is

adapted to be swung outwardly to permit lateral withdrawal of one or both bottles. Normally, the adjustable flange portion 31, conjointly with the fixed flange portions 30, serves snugly to encircle the upper ends of the stoppered bottles, thereby preventing unauthorized removal of the bottles.

As in the previous embodiment, a tongue 33 is adapted to project its end through a slot in the flange portion 31, and I have shown the tongue 10 provided with a perforation 34 adapted to receive a padlock.

In order to facilitate the grasping of the device of Figure 4, a handle 35 is preferably mounted on the top plate 29.

15 The present construction is particularly advantageous because of its inconspicuous character. Not only are cumbersome manipulations unnecessary, but the entire appearance of the set remains unimpaired.

20 While I have shown the tongue in each case provided with a perforation adapted to receive a padlock, it will be understood that other locking means may, if desired, be resorted to. It is contemplated that any suitable locking means may 25 be caused to engage with the projecting end of the tongue in order to prevent swinging of the adjustable flange portion.

It will also be understood that the device is 30 equally applicable to a single bottle, or to a set of bottles greater than two in number. Accordingly, in the appended claims, it is intended that the term "bottle" include within its significance either one, two, or more bottles. Also in the appended claims, I have used the term "stoppered bottle", and by this term I intend to allude to the 35 entire bottle, including the stopper.

40 While I have illustratively shown rectangular bottles with rectangular stoppers, it will be understood that bottles of other shapes and stoppers of other shapes may be employed. In general, it will be understood that changes in the details, herein described and illustrated for the purpose of explaining the nature of my invention, may be made by those skilled in the art without departing 45 from the spirit and scope of the invention as expressed in the appended claims. It is, therefore, intended that these details be interpreted as illustrative, and not in a limiting sense.

Having thus described my invention, and illustrated its use, what I claim as new and desire to 50 secure by Letters Patent is—

55 1. In a Tantalus set, the combination with a stoppered bottle, of a base plate adapted to support the bottle thereon, a top plate, connecting means at opposite edge portions of the top plate and the base plate for supporting the top plate and cooperating therewith to encircle the upper portion of the bottle with the top plate in position to snugly overlie the bottle stopper, a flange on one of said plates comprising a fixed portion and a complementary adjustable portion, said flange portions normally serving conjointly to encircle the adjacent end of the bottle to prevent withdrawal of the latter, said adjustable portion being adapted to be swung aside to permit lateral withdrawal of the bottle, and means for locking said adjustable flange portion in normal position.

60 2. In a Tantalus set, the combination with a stoppered bottle, of a base plate adapted to support the bottle thereon, a top plate, connecting means at opposite edge portions of the top plate and the base plate for supporting the top plate

and cooperating therewith to encircle the upper portion of the bottle with the top plate in position to snugly overlie the bottle stopper, a flange on one of said plates comprising a fixed portion and a complementary adjustable portion, said flange 5 portions normally serving conjointly to encircle the adjacent end of the bottle to prevent withdrawal of the latter, said adjustable portion being adapted to be swung aside to permit lateral withdrawal of the bottle, and means for locking said adjustable flange portion in normal position, said means comprising a tongue mounted on said plate closely adjacent to the bottle, a slot in the adjustable flange portion to receive said tongue through it, and releasable locking means 10 engaging the end of said tongue.

3. In a Tantalus set, the combination with a stoppered bottle, of a base plate adapted to support the bottle thereon, a top plate, connecting means at opposite edge portions of the top plate 20 and the base plate for supporting the top plate and cooperating therewith to encircle the upper portion of the bottle with the top plate in position to snugly overlie the bottle stopper, a flange on one of said plates comprising a fixed portion 25 and a complementary adjustable portion, said flange portions normally serving conjointly to encircle the adjacent end of the bottle to prevent withdrawal of the latter, said adjustable portion being adapted to be swung aside to permit lateral 30 withdrawal of the bottle, and means for locking said adjustable flange portion in normal position, said means comprising a perforated tongue mounted on said plate, a slot in the adjustable flange portion to receive said tongue through it, 35 and a lock engageable within the perforation of said tongue.

4. In a Tantalus set, the combination with a stoppered bottle, of a base plate adapted to support the bottle thereon, a continuous strap attached to opposite edge portions of the base plate and encircling the upper portion of the bottle snugly overlying the bottle stopper, a flange on the base plate comprising a fixed portion and a complementary adjustable portion, said flange 40 portions normally serving conjointly to encircle the bottom of the bottle to prevent withdrawal of the latter, said adjustable portion being adapted to be swung aside to permit lateral withdrawal of the bottle, and means for locking said adjustable 45 flange portion in normal position.

5. In a Tantalus set, the combination with a stoppered bottle, of a base plate adapted to support the bottle thereon, a continuous strap attached to opposite edge portions of the base plate and encircling the upper portion of the bottle snugly overlying the bottle stopper, a flange on the base plate comprising a fixed portion and a complementary adjustable portion, said flange 55 portions normally serving conjointly to encircle the bottom of the bottle to prevent withdrawal of the latter, said adjustable portion being adapted to be swung aside to permit lateral withdrawal of the bottle, and means for locking said adjustable flange portion in normal position, said 60 means comprising a perforated tongue mounted on said base plate closely adjacent to the bottle, a slot in the adjustable flange portion to receive said tongue through it, and a lock engageable within the perforation of said tongue.
